UNITED STATES PATENT OFFICE.

SYLVANUS ALBERT REED, OF NEW YORK, N. Y.

SIGNALING SYSTEM.

No. 908,698.

Specification of Letters Patent.

Patented Jan. 5, 1909.

Application filed October 26, 1905. Serial No. 284,477.

To all whom it may concern:

Be it known that I, SYLVANUS ALBERT REED, a citizen of the United States, residing in the city, county, and State of New York, 5 have invented certain new and useful Improvements in Signaling Systems, of which the following is a full, true, and concise specification.

My invention relates to selective signaling 10 and especially to an arrangement of ground connections for telephone party lines, which will allow circuits to be kept normally conductively discontinuous by means of condensers, will maintain a balance and guard 15 against inductive or ground disturbances, will offer across the line an impedance sufficient to protect the talking circuit, and may be capable of selective signaling.

The principle of the invention and several 20 modes of applying the same are hereinafter fully disclosed and more particularly pointed out in the accompanying claims.

Referring to the accompanying drawing:— Figure 1 represents an application of the 25 principle of my invention to a two party line using ordinary alternating or pulsating currents for ringing; Fig. 2 an application of the same to a four (4) party line, using biased bells which are adapted to be selectively operated by a current capable of ringing plus or minus through a condenser; Fig. 3 a modified arrangement of the impedance in a two party line; Fig. 4 represents the 30 same modification applied to a four party line, and Fig. 5 is a detail of a station modification.

Referring to Fig. 1, R—R¹ are signal receiving annunciators or telephone ringers, —R being at station A, and R¹ at station B 40 on a bridge respectively, across the party line M N leading to a central station at which the said line terminates in an ordinary jack J. References m n are the strands of a switchboard cord terminating in the plug 45 P—, and a, b, are ringing keys adapted to apply current from alternating current generators G and G¹ in the appropriate manner for selectively ringing R or R¹ respectively. The bridge at station A is conductively interrupted by the condenser K therein which 50 may conveniently have a capacity of about 2 microfarads, and the bridge at station B is conductively interrupted by two or more

condensers K' and K² each of about 1 microfarad capacity. The ringer R of bridge A 55 may conveniently be of about 2,500 ohms resistance. The ringer R' is contained in a ground branch which leads from a point on the bridge B which is so located thereon as that there will be an equal impedance and 60 capacity in each side of it toward the line conductors, or so as to produce an equalization of disturbing ground currents between the two sides M N of the line, such equalization being conditioned by the location of the 65 grounds as will hereinafter be specified. The resistance of ringer R' may conveniently be of about 1875 ohms. Ringing key a—when operated, connects generator G in bridge across the strands of the cord m, n, and therefore 70 across the line M N, and it is evident that R¹ will not be affected by such ringing current, while R will be so affected. Ringing key b—connects generator G¹ between the two cord strands m n and the two sides 75 M N of the line in parallel, so that current will traverse the condensers K¹, K² in parallel and the two halves of the impedance I in parallel through the ringer R¹ to ground, and it is evident that, provided there is a 80 balance of conditions in the two parallel branches for the current just named, ringer R will not be affected by current from generator G¹, while ringer R¹ will be so affected. Current from generator G¹ will divide in 85 opposite directions through the halves of coil I, and consequently the impedance of I will be neutralized and the resistance reduced to one quarter, while the joint capacity of the two condensers K¹, K², in multiple will be 90 double that of each or equal to that of K in bridge A. Either ringer may be operated by the depression of the appropriate key and disturbance from ground currents is obviated. 95

Referring now to Fig. 2—M, N, are the two sides of a party line having four (4) stations, A—A¹—B—B¹, and terminating in jack J, at an operating station or exchange, whereby they may be connected respectively by plug P to the strands m, n, of a switchboard cord. The selective ringing keys a, a', b and b' are adapted to connect to the line the generators G, G¹ or G² in appropriate manner to actuate the ringers R, R¹, R² 100 and R³ respectively. The latter ordinarily 105

are signal receiving annunciators or telephone ringers biased "plus" or "minus" as indicated in the drawing, ringers R , R^1 having each a resistance of about 2,500 ohms and ringers R^2 and R^3 having each a resistance of about 1,875 ohms. The ringers R , R^1 are each connected in series in their station bridges with condensers K and K^1 of about two microfarads capacity each, and ringers R^2 , R^3 are located in ground branches connected to the appropriate balancing point of their respective station bridges. The latter contain impedance and capacity elements as indicated by the coils I , I^1 and the condensers K^2 , K^3 , K^4 and K^5 , the said elements being arranged so that each bridge has its impedance and its condenser in series on both sides of its said balancing point. The impedance coils have about 2,500 ohms resistance. The condensers render the sides M , N , conductively separated. The generators G , G^1 and G^2 are specially constructed with reference to the line conditions, to produce a current which will create a difference of potential between the opposed condenser surfaces, first abruptly or cumulatively and then gradually or non-cumulatively and vice versa, so that the condenser-affected current which passes into the ringers will be alternately superior or inferior in motor effect to the bias tensions thereof and may be reversed at will to cause the superior current to be either of plus or minus polarity, whereby either of the oppositely biased ringers may be operated. The generator G , when connected to the line by the operation of key a , delivers current to the line conductors M , N , which produces an establishment or disestablishment of a difference of potential between the condenser surfaces of K and K^1 in the above manner so that the plus current will be superior and will actuate the armature of R while the minus current is ineffectual to overcome the bias tension of the armature of R^1 . The ringers R^2 and R^3 will obviously be not actuated for the same reasons as explained in connection with Fig. 1. Similarly when key a' is operated, the generator G being thereby reversely connected the ringer R^1 is actuated to the exclusion of the others. Key b —is adapted when operated to deliver current from generator G^2 through the two sides of the line in parallel to ground through ringers R^2 , R^3 ; and key b' is adapted when operated to deliver current from generator G^1 through the two sides of the line in parallel to ground through ringers R^2 , R^3 , and if the line is in substantial balance neither of such currents will affect ringers R , R^1 . Furthermore G^2 is adapted to produce in conjunction with the condensers, a current to which the positively biased ringer R^2 alone is responsive, the same as above explained, and G^1 a current to which

the negatively biased ringer R^3 alone is responsive, this being effected according to the principle of selection above explained. Consequently the operation of key b rings selectively the bell at station B —and the operation of key b' rings selectively the bell at station B^1 . Current from generators G^1 , G^2 , will divide in opposite directions through the halves of the coils I , I^1 , respectively, and the impedances of I , I^1 will be neutralized, while the resistances will be reduced one quarter, and the joint capacity of the two condensers K^2 , K^3 in parallel will be double that of each, as will be also that of the two capacities K^4 , K^5 in parallel. The ringing circuit from any of the generators will therefore in the preferred case be of equal resistance except for the line resistance and will be through equal capacities.

In Fig. 1 the telephone talking apparatus is shown included at station B in a bridge across the line. Provided there are no other grounds but those specified and that the impedances are equal in the bridge for each side of the ground connection, it will be free from disturbances due to varying potential difference at the ground connections of the circuit, on account of the fact that such disturbing current will divide equally between the two sides of the line in parallel, and in addition will pass with difficulty through the impedances of the grounded ringers. The same conditions obtain in Fig. 2. The impedances I , I^1 protect the talking circuit from short circuit in the same manner as the ringers R , R^1 so protect the talking circuit. In fact the protection will be better, on account of the fact that the capacities of the two condensers K^1 , K^2 (Fig. 1) in series is half the capacity of each singly and the same is true in Fig. 2 of the two condensers K^2 , K^3 in series, or the two condensers K^4 , K^5 in series.

Certain telephone switchboard circuits include a ground branch at some point which cannot be conveniently disconnected during ringing. Such a ground branch may deflect a part of the ringing current when ringing across the line as described with relation to Figs. 1 and 2, so that part of the current would pass through the grounded ringers and thus vitiate the selection. Figs. 3 and 4 exhibit a modification of the grounded ringer circuits to meet such a contingency. The permanent ground branch in these circuits is shown at C (Figs. 3 and 4) in the form of a cut-off relay connected to one side N , of the jack J , and the adaptation of the circuit consists in constituting the ringer R^2 (Fig. 3) as a part of the impedance. That is to say, the ground branch at station B leads to a balancing point which is located between the impedance of the ringer on one side and the impedance of coil I^1 on the

other, condensers being included in the station bridge as in the cases first described. The ringer R^4 is on that side of the balancing point which is not grounded by the 5 cut-off relay.

The ringing generator G^4 is grounded on one side and in the case of key b of Fig. 3, the operation of the key grounds the side, M , of the line at the same time that the side 10 N connects to the grounded generator, the side to be grounded being in every case that in which the ringers in the impedance bridges are placed. The effect of this ground at key b is to short circuit the ringer 15 R^4 so that current from G^4 will reach N through the impedance I^4 and leave the ringer R^4 silent. Ringer R will, however, respond as it will be in a branch of the main-circuit established by the key and its share 20 of the ringing current will depend upon the resistance of I^4 which may be made sufficient to divert the necessary ringing current to R . Ringer R^4 is rung by the operation of key a which connects both sides of the line to 25 one pole of the generator, the other pole being grounded, thereby causing a current to travel through both sides of the line in parallel to the condensers K^1 and K^2 in parallel, and through the ringer R^4 in parallel with 30 the coil I^4 to ground. Ringer R will be unaffected by the current for obvious reasons.

Carrying the same principle of arrangement to the four party line of Fig. 4, R , R^1 are oppositely biased ringers in two bridges, 35 broken by condensers K and K^1 respectively. R^5 and R^6 are similar ringers in line bridges which are respectively interrupted as to their conductive continuity by condensers K^2 , K^3 and K^4 , K^5 respectively, the said 40 ringers being each located in the bridge on the opposite side of the ground connection from the impedance coils I^6 , I^5 respectively; and on that side of the said point which is not grounded by the cut-off relay C . The 45 generators G^4 , G^5 are appropriately connected with the keys a , a' , b , b' and with ground to produce a selective actuation of the ringers at the several stations according to the key which is operated, exactly as in 50 the case described with reference to Fig. 2, but with the protection against the ground in line N through the relay C , as has been described with reference to Fig. 3. The operation will be apparent from an examination of the circuit without tracing the several paths. The telephone talking apparatus for this modified form of system may be applied as shown in Fig. 3 so that it will be connected in bridge across the line 55 and interrupt the ground connection when in use, but will close such connection when not in use. The same talking apparatus can obviously be applied to the stations of Fig. 4.

In each of the foregoing cases, it will be

evident that the relative positions of the 65 impedance and capacity elements may be reversed, without vitiating the conditions of successful operation. Such an arrangement is illustrated for convenience in Fig. 5. I do not confine myself to the specific order of 70 impedance and capacity above described, but may use such other sequence as will not alter the condition of conductive discontinuity of the ground branches, selection in ringing, impedance across line to talking 75 current and a balance to ground disturbances.

I am aware that the device of an inductance across a line with a ground branch from the middle point is familiar in the art 80 as a means of attaining two non-interfering circuits, but the adjustment to a balance to eliminate the effect of ground disturbances to voice currents is a novel and important feature which I wish to be understood as 85 claiming herein.

Having described my invention, what I claim and desire to secure by United States Letters Patent is:

1. In a signaling system, a party line having a pair of bridges thereacross, branches to ground from said bridges, and impedance elements and condensers in each bridge located therein on each side of the ground branches thereof and adjusted to divert 95 ground currents equally to both sides of the line, in combination with a pair of oppositely biased annunciator elements respectively connected with each bridge and adapted to be operated by current of 100 appropriate direction passing through the ground branch, and a source of current adapted to be connected with both sides of the line and ground, and to produce a current which will alternately change the potential difference of the bridge condensers abruptly and gradually or vice versa, whereby the condenser affected current will be alternately superior and inferior in motor effect to the bias tensions of said annunciator 110 element.

2. In a selective four party signaling line, two bridges thereacross containing respectively oppositely biased ringers and condensers in series therewith, two other bridges 115 each connected with ground and containing condensers and impedance elements on each side of the grounded points, adjusted to divert ground currents equally to both sides of the line, and oppositely biased ringers 120 respectively associated with each said last named bridges to be operated by appropriate current passing through the ground branches thereof, in combination with means of impressing current on the line to charge the 125 condensers alternately, abruptly and gradually or vice versa, and switches for passing said current through said first named

bridges in series with the sides of the line, or through the last named bridges and both sides of the line in multiple and through ground, the condenser affected current in
5 said ringers being alternately superior and inferior in motor effect to their bias tensions.

In testimony whereof, I have signed my

name to the specification in the presence of two subscribing witnesses.

SYLVANUS ALBERT REED.
